BOTTOM RAIL ASSEMBLY FOR VENETIAN BLINDS

Filed Feb. 13, 1945

Fig. 1.

UNITED STATES PATENT OFFICE

2,421,505

BOTTOM RAIL ASSEMBLY FOR VENETIAN BLINDS

Joseph L. Hunter, Riverside, Calif., assignor to
 Hunter Engineering Co., Riverside, Calif., a
 corporation of California

Application February 13, 1945, Serial No. 577,691

5 Claims. (Cl. 160—173)

1

My invention relates to the construction of bottom rails for Venetian blinds and has particular reference to a construction for the same in which the bottom rails may be made of metal particularly adapted for use with Venetian blinds formed with metal slats.

In the construction of Venetian blinds it has recently become the practice to construct such Venetian blinds with the slats formed of strips of metal as distinguished from the previous wood slat constructions and it is desirable that with such metal slat blinds a bottom rail structure also formed of metal be employed. Moreover, in Venetian blind assemblies of relatively great length, it is desirable to provide a relatively great number of lifting and lowering cords for suspending the blind structure, necessitating the passing of the cords over pulley assemblies located upon the bottom rail structure in order that all of the lifting and lowering cords may be raised and lowered by a single lifting and lowering mechanism.

It is therefore an object of my invention to provide a bottom rail structure for Venetian blinds which may be readily formed of sheet metal in the shape of an elongated flattened hollow tube.

Another object of my invention is to provide a Venetian blind bottom rail structure of the character set forth in which the bottom rail structure may be formed in any desired commercial lengths and then may be cut to fit the particular length of a Venetian blind as desired and the cut ends finished with end closures press-fitted into the ends of the tubular bottom rail.

Another object of my invention is to provide a bottom rail structure for Venetian blinds of the character set forth wherein cord pulleys may be disposed within and concealed within the hollow tubular bottom rail assembly.

Another object of my invention is to provide a pulley structure which may be employed within the hollow bottom rail structure, which is relatively simple in construction and inexpensive to manufacture.

Another object of my invention is to provide a pulley of the character set forth wherein the pulley may be assembled and held in place within the bottom rail structure by the same attaching means which is employed to secure the ladder tapes to the bottom rail.

Other objects and advantages of my invention will be apparent from a study of the following specifications, read in connection with the accompanying drawings, wherein

Fig. 1 is a perspective view of a portion of a

2

Venetian blind assembly illustrating the manner in which my bottom rail assembly may be used;

Fig. 2 is a fragmentary exploded perspective view of a portion of the bottom rail structure shown in Fig. 1 and illustrating the manner in which the end closure may be assembled therewith;

Fig. 3 is a transverse sectional view taken through a bottom rail structure constructed in accordance with my invention, illustrating the mounting therewithin of a cord pulley concealed within the bottom rail structure; and

Fig. 4 is a fragmentary longitudinal sectional view through a portion of a bottom rail and pulley assembly such as that illustrated in Fig. 3.

Referring to the drawings, I have illustrated in Fig. 1 a typical assembly of a slat supporting ladder comprised of a pair of parallel extending tapes 1 and 2, between which, as will be understood by those skilled in this art, there extends a number of cross webs or bars (not shown) upon which the slats of the assembled blind may rest. The ladder tapes 1 and 2 are illustrated as passing downwardly along the side edges of a bottom rail assembly 3 to be secured to the underneath surface of the bottom rail assembly 3 as by means of a tape fastener illustrated at 4 in Figs. 3 and 4 and adapted to be covered and enclosed by a cover plate 5 secured to the bottom rail structure 3 as by means of screws 6. The bottom rail assembly 3 is preferably constructed as a length of elongated flattened hollow tube 7 which, if desired, may be formed as a seamless tube or may be inexpensively constructed as by forming a pair of channel members 7a and 7b, the side flanges of the channel 7a receiving therebetween the side flanges of the channel 7b, the two channels being secured together by any suitable means such as a series of spot welds 8.

The bottom rail tube may be factory fabricated in any desired commercial lengths and may then be cut to lengths adapted for a particular blind assembly and the ends of the tube may then be finished off by means of metal closures 9, preferably stamped or formed in the shape indicated in Fig. 2, the inner end 10 thereof being slightly less dimensions than the major and minor transverse axes of the tube 7 so as to permit the closure member 9 to be pressed into the cut end of the tube 7. The closures 9 are preferably formed with projecting lips 11 at opposite side edges thereof to comprise abutments against which the ends of the side edges of the tube 7 may abut to prevent the closures 9 from being inadvertently pressed wholly within the tube 7. The lips 11

constitute also abutments against which a screw-driver, chisel or other tool may be engaged when it is desired to disassemble the closure 9 from the tube end with which it is associated.

It will be observed that the tubular bottom rail member 7 provides ample space within its interior for the reception and mounting of cord pulleys wherever it is desired to pass lifting and lowering cords from the bottom of the blind to the bottom rail and then along the bottom rail and back up to the top of the blind. A simple and inexpensive form of pulley adapted for this purpose is illustrated particularly in Figs. 3 and 4 as comprising a metal bracket 12 having a pair of up-turned parallel ears 13 through which extends a pin 14 constituting the bearing upon which a spool pulley 15 is mounted. An opening 16 formed in the lower surface of the tube 7 immediately below a cord aperture 17 formed in the upper surface thereof permits the insertion of the pulley assembly 13, 14 and 15 into the hollow space 18 formed within the tube 7, the pulley being held in place by any suitable means such as screws 6 which, in the form of apparatus illustrated in Figs. 3 and 4, also are employed to secure the lower ends of the adjacent tapes 1 and 2 to the bottom rail assembly. A tape fastening plate 19, such as that illustrated, described and claimed in my copending application Serial No. 577,692, filed February 13, 1945, need not be described here other than to point out that the plate 19 is formed with a pair of tongues 20 struck from the plate 19 to provide a space 21 through which the tapes 1 or 2 may be drawn and then folded back beneath the tongues 20 to hold the tapes 1 securely in position.

To facilitate the assembly of the cover plate 5, the tape fastening plate 19 and the pulley bracket 12 by the same screws 6, it is only necessary to provide the bracket 12 with a pair of apertures 22 and 23 spaced longitudinally of the rail by the same spacing as the apertures through which the screws 6 extend through the cover plate. Thus the assembly of all of the structure may be made by a single pair of screws 6.

It will therefore be observed that I have provided a bottom rail structure which may be readily and inexpensively constructed of metal in the form of a hollow tube finished off at its ends by means of closures merely press-fitted into the ends of the desired length of tubular bottom rail and that such bottom rail structure, being hollow, provides a space in which the necessary or desired pulley and cord structures may be mounted and concealed within such tubular bottom rail.

While I have shown and described the preferred embodiment of my invention, I do not desire to be limited to any of the details of construction shown and described herein, except as defined in the appended claims.

I claim:

1. In a bottom rail structure for Venetian blinds, the combination of an elongated tubular member having a flattened cross section, and a closure member for each end of said tubular member comprising a substantially cup-shaped closure having a transverse cross section corresponding to the transverse cross section of said

tubular member, the side walls of said closure member being snugly insertable into the end of said tubular member, the base of the cup-shape closure having at least one dimension in excess of the corresponding internal dimension of the tubular member.

2. In a bottom rail structure for Venetian blinds, the combination of an elongated tubular member having a flattened cross section, and a closure member for each end of said tubular member comprising a substantially cup-shaped closure having a transverse cross section corresponding to the transverse cross section of said tubular member, the side walls of said closure member being snugly insertable into the end of said tubular member, and having at each of its ends an outwardly projecting lip to abut the end of the tubular rail member and to prevent insertion of said closure wholly within the tubular member.

3. In a bottom rail for Venetian blinds, an elongated tubular member having a substantially flattened cross section, a cord pulley mounted within and concealed within said tubular member, said cord pulley comprising a bracket secured to the lower face of said rail member and having a pair of upwardly projecting parallel ears extending into the interior of said tubular rail member, and a pulley member rotatably mounted upon said ears.

4. In a bottom rail assembly for Venetian blinds, a bottom rail comprising a hollow tubular member of substantially rectangular cross section, means on the lower face of said rail member for engaging and fastening Venetian blind ladder tapes thereto, a pulley means mounting a cord pulley within said tubular member, and screw means extending through said tape fastening means and said pulley means for simultaneously securing said fastening means and said means to said rail member.

5. In a bottom rail assembly for Venetian blinds, a bottom rail comprising a hollow tubular member of substantially rectangular cross section, means on the lower face of said rail member for engaging and fastening Venetian blind ladder tapes thereto, a pulley means mounting a cord pulley within said tubular member, a cover plate disposed below said fastening means to cover and conceal the same, and screw means extending through said cover plate, said fastening means and said pulley means and into engagement with the lower side of said rail member for simultaneously securing all of said members together.

JOSEPH L. HUNTER.
